UNITED STATES PATENT OFFICE.

HENRY S. YOUNG, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

SIGNALING APPARATUS.

Application filed May 21, 1925. Serial No. 31,778.

My invention relates to signaling apparatus, and particularly to apparatus of the type comprising a highway crossing signal located adjacent the intersection of a railway and a highway and controlled by traffic conditions in the adjacent stretch of railway track.

I will describe two forms of signaling apparatus embodying my invention, and will then point out the novel features thereof in claims.

In the accompanying drawing, Fig. 1 is a diagrammatic view illustrating one form of signaling apparatus embodying my invention. Fig. 2 is a view showing a modified form of the apparatus illustrated in Fig. 1, and also embodying my invention.

Similar reference characters refer to similar parts in both views.

Referring first to Fig. 1, the reference characters 1 and 1^a designate the track rails of a stretch of railway track which is intersected by a highway H. By means of insulated joints 2 the track rails 1 and 1^a are divided into two insulated track sections A—B and B—C, the junction B of these two track sections being located at or near the highway crossing H. A track transformer T' has its secondary 4 connected across the rails adjacent the left hand end of section A—B. A similar track transformer T² has its secondary 4 connected across the rails adjacent the right hand end of section B—C. An impedance 6 is interposed between the secondary 4 of each transformer T and the rails of the associated section in the usual manner. The primary 5 of each of the track transformers T is constantly supplied with alternating current from some suitable source, such as an alternator M, over line wires 3 and 3^a.

A track relay R' is connected across the rails adjacent the right hand end of section A—B, and a similar track relay R² is connected across the rails adjacent the left hand end of section B—C. It will therefore be seen that each track section is provided with a track circuit including the secondary of a track transformer, a track relay, and the two track rails of the section in series. Associated with each of the track relays R is a slow releasing stick relay designated by the reference character K with an exponent corresponding to the location.

These stick relays are at times supplied

with energy from secondary 7 of a line transformer D, the primary 8 of which is constantly supplied with energy over line wires 3 and 3^a.

Referring particularly to relay K', this relay is provided with a pick-up circuit over which current flows from secondary 7 of transformer D, through wires 9 and 10, back contact 11 of relay R', wires 12 and 13, back contact 14 of stick relay K², wire 15, winding of relay K', and wires 16, 17 and 18 back to secondary 7 of transformer D. This circuit is closed only when relays R' and K² are de-energized. Relay K' is also provided with a stick circuit which passes from secondary 7 of transformer D, through wires 9 and 19, back contact 20 of relay R², wires 21 and 22, front contact 23 of relay K', wires 24 and 13, back contact 14 of relay K², wire 15, winding of relay K' and wires 16, 17 and 18 back to secondary 7 of transformer D. The stick circuit just traced is closed only when relay K' is already energized and relays R² and K² are both de-energized.

Stick relay K² is controlled by relays R², R' and K' in the same manner as just described for the control of relay K' by relays R', R² and K².

Located adjacent the crossing of highway H with the railway track is a highway signal designated by the reference character S. This signal is arranged to give a warning indication when energized but not when de-energized, and is here illustrated as an electric bell by the customary symbol.

The signal S is provided with two operating circuits. One of these circuits passes from secondary 7 of transformer D, through wires 9, 10 and 25, back contact 26 of relay R', wire 27, back contact 28 of stick relay K², wires 29 and 30, operating mechanism of signal S, and wires 31 and 18 back to secondary 7 of transformer D. This circuit is closed only when relays R' and K² are both de-energized. The second circuit for signal S passes from secondary 7 of transformer D, through wires 9, 19 and 32, back contact 33 of relay R², wire 34, back contact 35 of relay K', wire 30, operating mechanism of signal S, and wires 31 and 18 back to secondary 7 of transformer D. The circuit last traced is closed only when relays R² and K' are both de-energized.

As shown in the drawing all of the parts of the apparatus occupy the positions cor-

responding to the normal or unoccupied condition of the trackway. Under these conditions relays R' and R^2 are both energized, relays K' and K^2 are both de-energized, and signal S is de-energized.

In explaining the operation of the apparatus I will first assume that an eastbound train, that is, a train moving from left to right, enters the stretch of track shown in 10 the drawing. When this train enters section A—B relay R' becomes de-energized. The closing of back contact 11 of this relay completes the pick-up circuit for relay K' which relay then becomes energized. At 15 the same time the closing of back contact 26 of relay R' closes the operating circuit for signal S over back contact 28 of relay K^2 , now de-energized. Signal S therefore is operated to give a warning indication. 20 When the train enters section B—C relay R^2 becomes de-energized. The closing of back contact 20 on this relay does not complete the pick-up circuit for relay K^2 , however, because this pick-up circuit is now 25 open at back contact 23 of relay K' . Relay K^2 therefore remains in its de-energized condition and signal S continues to display a warning indication.

When the train moves out of section A—B 30 relay R' becomes energized, thereby interrupting the pick-up circuit for relay K' , but this relay is now maintained in its energized condition over its stick circuit including back contact 20 of relay R^2 . The opening of back contact 26 of relay R' interrupts one operating circuit for signal S' and the other operating circuit for this signal is now open at back contact 35 of relay K' . Signal S is therefore de-energized and ceases to 35 give a warning indication. If, however, a following train should enter section A—B the de-energization of relay R' would immediately complete the operating circuit for signal S and cause that signal to give a 40 warning indication. It follows that the crossing is at all times fully protected no matter how closely one train follows another.

When the train moves out of section B—C, relay R^2 becomes energized and opens the stick circuit for relay K' , allowing this relay to open, and restoring the apparatus to its normal condition.

The operation of the apparatus for west-bound trains is exactly the same as just described in connection with eastbound trains and will be readily understood from the drawing without further explanation.

With very short, light trains such as a 60 switching engine and tender it may happen that the brief interval of time elapses after the train leaves section A—B and before the de-energization of relay R^2 , in an east-bound move. During this time interval 65 both the pick-up circuit and the stick cir-

cuit for relay K' will be open. Due to the slow acting characteristic of the relay K' however, the relay will bridge this time interval and will maintain its front contacts closed.

70

It may also be desirable under some conditions to separate the adjacent ends of sections A—B and B—C by a short insulated portion of track. This might be desirable where an electric railway crosses the 75 track on the highway H. Under these conditions the slow acting relays K will bridge the time interval required for a train to pass from one track section to the other. The signal S therefore ceases to give a warning indication after the train has passed the crossing.

80

Referring now to Fig. 2 the apparatus here illustrated is exactly the same as that already described in connection with Fig. 1 85 except for the control of the highway crossing signal. In Fig. 2 the electric bell S is replaced by wig-wag signal S' . This signal, in accordance with usual practice, has a holding winding which, when energized, latches the pendulum in one extreme position wherein the signal indicates clear. When this winding is de-energized, it sets 90 into operation a motor which causes the pendulum to swing back and forth and the signal then gives a warning indication. One form of signal operating in this manner is shown and described in Letters Patent of the United States No. 1,498,157, granted to C. W. Dunham on June 17, 1924, for 95 highway crossing signal. The motor is provided with an operating circuit which passes from secondary 7 of transformer D, through wires 9^a, 9, 19 and 45, operating mechanism of signal S' and wires 44 and 18 back to secondary 7 of transformer D. The circuit for the holding winding comprises three branches, one of which passes from secondary 7 of transformer D, through wires 9^a, 9, 19, 36 and 37, front contact 38 of relay R^2 , wires 39 and 40, front contact 41 of relay R' , wires 42 and 43, operating mechanism of signal S' and wires 44 and 18 back 100 to secondary 7 of transformer D. The holding circuit is closed through this branch 105 only when relays R' and R^2 are both energized, under which condition signal S' displays its clear indication. Another branch 110 of the holding circuit may be traced from secondary 7 of transformer D, through wires 9^a and 46, front contact 47 of relay K' , wires 48, 49 and 40, front contact 41 of relay R' , wires 42 and 43, operating mechanism of signal S' , and wires 44 and 18 back 115 to secondary 7 of transformer D. The holding circuit is closed through this branch only when relays R' and R^2 are both energized, under which condition signal S' displays its clear indication. Another branch 120 of the holding circuit may be traced from secondary 7 of transformer D, through wires 9^a and 46, front contact 47 of relay K' , wires 48, 49 and 40, front contact 41 of relay R' , wires 42 and 43, operating mechanism of signal S' , and wires 44 and 18 back 125 to secondary 7 of transformer D. Still another branch for the holding circuit may be traced from secondary 7 of transformer D, through wires 9^a, 9, 19, 36 and 37, front contact 38 of relay R^2 , wires 39, 49 and 50, front contact 51 of relay K^2 , wires 52 and 130

43, operating mechanism of signal S' and wires 44 and 18, back to secondary 7 of transformer D.

Under normal conditions, that is, when the stretch of track shown in the drawing is unoccupied, relays R' and R^2 are both energized and relays K' and K^2 are both de-energized as has already been explained. Under these conditions the holding circuit for signal S' is complete over front contact 41 of relay R' and front contact 38 of relay R^2 and the wigwag signal is therefore latched up. If, now, a train enters section A—B relay R' becomes de-energized, and relay K' picks up. All of the branches of the holding circuit for signal S' are now open and the signal therefore displays a warning indication. When the train enters section B—C relay R^2 becomes de-energized but the rest of the apparatus is not affected and signal S' continues to display a warning indication. When the rear of the train leaves section A—B, relay R' becomes energized but relay K' is held closed over its stick circuit, relay R^2 now being de-energized. The energization of relay R' , however, completes one branch of the holding circuit for signal S' over front contact 41 of relay R' and front contact 47 of relay K' , so that the signal is latched up. If, however, a following train enters section A—B, the de-energization of relay R' immediately opens this holding circuit and signal S' again displays its warning indication. The same protection is therefore given for following trains as was the case with Fig. 1.

When the train moves out of section B—C relay R^2 becomes energized, opening the stick circuit for relay K' , and restoring the apparatus to its normal condition.

In Fig. 2, relays K' and K^2 are made slow acting for the same reasons as explained in connection with Fig. 1.

The operation of the apparatus shown in Fig. 2 for traffic from right to left is similar to that just described for the opposite direction and will be readily understood from the drawing.

Although I have herein shown and described only two forms of signaling apparatus embodying my invention, it is understood that various changes and modifications may be made therein within the scope of the appended claims without departing from the spirit and scope of my invention.

Having thus described my invention, what I claim is:

1. In combination, two adjacent sections of railway track, a track relay for each section, a stick relay associated with each said track relay, a pick-up circuit for each said stick relay including a back contact of the associated track relay and a back contact of the other stick relay; a stick circuit for

each stick relay including its own front contact, a back contact of the other stick relay, and a back contact of the track relay associated with such other stick relay; and a highway crossing signal controlled by said stick relays and by said track relays.

2. In combination, two adjacent sections of railway track, a stick relay for each section, means for energizing each said stick relay when a train enters the associated section moving toward the other section, means for maintaining each such relay in its energized condition until such train moves out of the other section, and a highway crossing signal controlled by said stick relays.

3. In combination, two adjacent sections of railway track, a track relay for each said section, a stick relay for each said section, means for energizing each said stick relay when a train enters the associated section moving toward the other section, means for maintaining each stick relay in its energized condition until such train moves out of the other section, means for preventing each stick relay from being energized when the other stick relay is energized, a highway crossing signal located adjacent the junction of said two track sections, and means for causing said signal to display its warning indication when the track relay for either section is de-energized and the stick relay for the other section is also de-energized.

4. In combination, two adjacent sections of railway track, a track relay for each section, a stick relay for each said section, means for energizing each said stick relay when a train enters the associated section moving toward the other section, means for maintaining each such relay in its energized condition until such train moves out of the other section, a highway crossing signal located adjacent the junction of said two track sections, means for controlling said signal by all of said relays so that the signal displays one indication when the track relay for either section is de-energized and the stick relay for the other section is de-energized, and a different indication at all other times.

5. In combination, two adjacent sections of railway track, a track relay for each said section, a stick relay for each said section, means for energizing each said stick relay when a train enters the associated section moving toward the other section, means for maintaining each such relay in its energized condition until such train moves out of the other section, means for preventing each stick relay from being energized when the other stick relay is energized, a highway crossing signal located adjacent the junction of said two track sections, and a controlling circuit for said signal including a back contact of one track relay and a back

contact of the stick relay for the other section.

6. In combination, two adjacent sections of railway track, a track relay for each said section, a stick relay for each said section, means for energizing each said stick relay when a train enters the associated section moving toward the other section, means for maintaining each such relay in its energized condition until such train moves out of the other section, means for preventing each stick relay from being energized when the other stick relay is energized, a highway crossing signal located adjacent the junction of said two track sections, a controlling circuit for said signal including a back contact of the track relay for one section and a back contact of the stick relay for the other section, and a second controlling circuit for said signal including a back contact of the remaining track relay and a back contact of the remaining stick relay.

7. In combination, two adjacent sections of railway track, a track relay for each section, a stick relay associated with each said track relay, a pick-up circuit for each said stick relay including a back contact of the associated track relay and a back contact of the other stick relay; a stick circuit for each stick relay including its own front contact,

tact, a back contact of the other stick relay, and a back contact of the track relay associated with such other stick relay; a highway crossing signal located adjacent the junction of said two track sections, a controlling circuit for said signal including a back contact of the track relay for one section and a back contact of the stick relay for the other section, and a second controlling circuit for said signal including a back contact of the remaining track relay and a back contact of the remaining stick relay.

8. In combination, two adjacent sections of railway track, a track relay for each section, a slow releasing stick relay associated with each said track relay, a pick-up circuit for each said stick relay including a back contact of the associated track relay and a back contact of the other stick relay; a stick circuit for each stick relay including its own front contact, a back contact of the other stick relay, and a back contact of the track relay associated with such other stick relay; and a highway crossing signal controlled by said stick relays and by said track relays.

In testimony whereof I affix my signature.

HENRY S. YOUNG.
